DESIGN FOR A PERFUME BOTTLE CONTAINER OR SIMILAR ARTICLE

Norbert R. Hahn, New York, N. Y., assignor to Coty, Inc., Wilmington, Del., a corporation of Delaware

Application July 27, 1940, Serial No. 93,972

Term of patent 14 years

To all whom it may concern:

Be it known that I, Norbert R. Hahn, a citizen of the United States, residing in the city and State of New York, have invented a new, original, and ornamental Design for a Perfume Bottle Container or Similar Article, of which the following is a specification, reference being had to the accompanying drawing, forming a part thereof.

In the drawing

bottle container showing my new design in an open position,

Figure 2 is a perspective view showing the article in the closed position; and

I claim:

The design for a perfume bottle container or similar article, as shown.

NORBERT R. HAHN.
